UNITED STATES PATENT OFFICE

QUIMBY S. BACKUS, OF WINCHESTER, MASSACHUSETTS.

DESIGN FOR A FOLDING BEDSTEAD.

SPECIFICATION forming part of Design No. 16,203, dated August 18, 1885.

Application filed July 10, 1885. Term of patent 14 years.

To all whom it may concern:

Be it known that I, QUIMBY S. BACKUS, a citizen of the United States, residing at Winchester, in the county of Worcester and State of Massachusetts, have invented and produced a new and original Design for Folding Bedsteads, of which the following is a specification, reference being had to the accompanying drawing, forming part thereof.

10 The principal feature of my design consists in the configuration and ornamentation of the under side of a folding bed, or that part of the bedstead which constitutes the front when folded, with a conventional representation of a fire-place and mantel, as shown in the drawing.

15 A is the bottom of a folding bedstead, or that portion thereof which forms the front of the bedstead when folded. The lower part of 20 this bed bottom or front represents a fire-place, B, above which is a mantel, C, supported on suitable brackets. Above the mantel is a panel-mirror, D, for which may be substituted

a picture or other ornament. The folding foot-board, with its legs, forms an ornamental cornice, E, above the mirror. The bedstead, when folded, thus presents to the eye the appearance of a fire-place with mantel and mirror.

I claim—

1. The design for a folding bedstead, which consists of the bottom or front thereof having the conventional representation of a fire-place and mantel, substantially as shown and described. 30

2. The design for a folding bedstead, which consists of the bottom or front A, having the conventional representation of a fire-place, B, with mantel C and mirror D, substantially as shown and described. 35

40 In testimony whereof I affix my signature in presence of two witnesses.

QUIMBY S. BACKUS.
